MIXING DEVICE

Samuel K. Nester, Geneva, N. Y., assignor to
Geneva Processes, Inc., a corporation of New
York

Application December 19, 1939, Serial No. 310,073

9 Claims. (Cl. 259—105)

My invention relates to mixers, beaters, grinders and similar apparatus for treating or agitating liquids or material mixed with liquids and particularly to constructions having mixing or agitating elements operable at different speeds.

Various types of mixers, beaters and grinders have been designed heretofore for forming emulsions, grinding pigments, dissolving or dispersing solids and for other purposes wherein beating, grinding or agitating members are positively driven at different speeds. However, such devices are frequently complicated and require continued adjustment to vary the relative speed of the elements in response to changes in condition of the material undergoing treatment. Moreover, special and expensive bearings are frequently required to maintain the mixing elements in proper relation and alignment.

In accordance with my invention these objections to mixers and beaters of the prior art are overcome and devices provided which are simple in construction and economical to produce and operate and which are automatically responsive to changes in the condition of the material undergoing treatment.

Devices embodying my invention are adapted for use in forming mixtures or emulsions of liquids; in grinding or mixing pigments, dyes or other materials suspended in a liquid medium; in dissolving, suspending or dispersing solids in liquids, and in many other operations wherein a liquid medium is employed. However for simplicity in describing my invention all such devices are hereafter referred to as "mixers" and certain of the operating elements are referred to as "mixing elements" although their function in some instances may be primarily that of a grinding element, scraper or stirrer.

A characteristic feature of constructions embodying my invention resides in the use of a floating mixing element which is impositively driven through the action of material undergoing treatment so that as the viscosity or other properties of the material change during operation the speed and force with which said element is driven are correspondingly altered.

Another characteristic feature of my invention resides in novel bearing and aligning means employed for insuring proper operation of the mixing elements and the maintenance of such elements in the proper relation to each other.

One of the objects of my invention is to provide a novel type of mixing device or the like which is simple in construction, economical to

produce and operate and adapted for use in the treatment of a wide variety of materials.

Another object of my invention is to provide a mixing device or the like having a plurality of mixing elements one of which is positively driven and another of which is impositively driven.

A further object of my invention is to provide a mixing device or the like with novel means for maintaining the mixing elements in the desired cooperative relation.

A specific object of my invention is to provide a mixing device or the like with a floating mixing element impositively driven by the action of the material undergoing treatment.

These and other objects and features of my invention will appear from the following description thereof in which reference is made to the figures of the accompanying drawing.

In the drawing:

Fig. 1 is a vertical sectional view through a typical mixing device embodying my invention, and

Fig. 2 is a horizontal sectional view through the mixing device of Fig. 1, taken on the line 2—2 thereof.

In that form of my invention illustrated in the drawing the mixing device is provided with a high speed mixing element 2 secured to a shaft 4 which in turn is connected to a motor 6 by a coupling 8. A low speed mixing element 10 is rotatable about the shaft 4 in the same direction as the element 2 but at a lower speed. An anti-friction bearing 12 serves to maintain the shaft 4 and the upper portion of the low speed mixing element in proper alignment while means on the lower portion of the element 10 cooperate with the high speed mixing element 2 to provide a floating bearing for centering the lower end of the low speed mixing element with respect to the element 2.

The form of the high speed mixing element may be varied considerably to adapt the device for any particular operation but as shown the element 2 is in the form of a disc having an outwardly inclined peripheral surface 14 and is provided with fins or impelling blades 16 secured to the upper surface of the disc to force material radially outward toward the surface 14 on rotation of the disc.

The low speed mixing element 10 also may be varied considerably for any preferred use of the device but preferably it is formed with a lower member 18 having a central opening 20 through which the shaft 4 extends and into which the material being treated passes to the high speed

mixing element during operation. The lower surface of the member 18 adjacent the opening 20 is inclined downwardly and outwardly and spaced from the upper face of the disc 2 to form a chamber for receiving material to be treated. The outer portion 22 of the lower surface of member 18 is substantially parallel to the surface 14 of the high speed mixing elements and is spaced only a short distance therefrom.

With this construction material entering the central opening 20 is impelled outward against the lower surface of the member 18 by the blades 16 on rotation of the element 2. The material is thus forced between the spaced surfaces 14 and 22 of the mixing elements so that the low speed mixing element is raised slightly and caused to float or ride upon a film of the material undergoing treatment and passing between the cooperating surfaces of the mixing elements. At the same time the material, being fluid, tends to distribute itself uniformly about the element 2 and between the surfaces 14 and 22 centering the member 18 with respect to the element 2. The material thereby functions as a floating bearing to maintain the surfaces 14 and 22 in the desired operative relation.

The material in contact with and located adjacent the surface 14 of the high speed mixing element tends to rotate therewith and so causes the low speed mixing element to rotate in the same direction as the element 2 but at a lower speed.

In order further to aid in dispersion or mixing of the material under treatment and in order to overcome any tendency for the floating low speed mixing element to rotate in unison with or at substantially the same speed as the high speed mixing element, the low speed mixing element is provided with agitator members which are suitably formed to stir the material or to direct it either inward toward the center or outward toward the walls of the vessel or they may be arranged to scrape material from the walls or bottom of the vessel or to perform other functions. The agitator members illustrated are in the form of cylindrical beater rods 24 which extend upward from the member 18 to mix or stir the material and retard the rotation of the low speed mixing element.

Thus the surface 22 of the slow moving member 18 cooperates with the surface 14 of the rapidly rotating element 2 to cause material passing between the same to be dispersed, emulsified, ground or agitated to produce the desired result.

The agitating members also serve to break up any eddy currents which might tend to catch up light particles or other material and cause them to circulate in a path adjacent the walls of the vessel or elsewhere out of the current of material passing to the high speed mixing element. Such agitation further opposes the formation of a vortex about the shaft 4 so that while agitating the material they prevent the passage of air into the space between the surfaces 14 and 22 and insure the maintenance of a film of material between these surfaces at all times during operation.

The upper ends of beater rods 24 are connected to a cross bar 26 which has a central cage 28 surrounding the anti-friction bearing 12 on the shaft 4. The cage 28 is axially movable relative to the bearing 12 so that the whole low speed mixing element may move longitudinally of the shaft 4 to provide the desired

floating characteristics for said element and to permit separation of the member 18 from the element 2 in the event a lump of material or foreign matter attempts to pass between the surfaces 14 and 22 of the mixing elements.

If the cage 28 and the low speed mixing element are permitted to descend until the surface 22 of the member 18 engage the surface 14 of the element 2 there will be a direct frictional drive between the elements until the low speed mixing element is raised by material forced between the surfaces 14 and 22 by the impeller blades 16 and centrifugal force. However, generally it is preferred to maintain a predetermined initial or minimum clearance between the surfaces 14 and 22 and therefore an adjusting nut 30 is applied to the shaft 4 adjacent the lower surface 32 of the cage 28. By adjustment of the nut 30 it is then possible to vary the clearance between the surfaces 14 and 22 as desired to permit contact thereof or to maintain a minimum space therebetween. In some instances also it is desirable to urge the floating low speed mixing element down toward the high speed element 2 or to limit upward movement thereof and therefor a spring 34 is positioned to bear against the upper surface 36 of the cage 28 to force it downward. The upper end of the spring 34 bears against suitable means such as a collar 38 carried by the shaft 4.

The apparatus preferably is of a portable type and provided with a cover or support 40 adapted to engage the upper edge of a tank or other vessel 42 containing the material to be treated. In this way the device may be moved from one vessel to another at will and may be removed for cleaning or to permit the material to be subjected to other operations in the same vessel. Moreover, the vessel need have no lower bearing member for supporting or centering the mixing elements so that the device may be inserted directly into a conventional drum or container in which the material is received or shipped.

In using the apparatus described for producing a typical dye containing emulsion the high speed mixing element is formed with the surface 14 thereof inclined at an angle of about 60° and preferably smooth, rather than serrated as it is when used primarily for grinding purposes. The inner surface 22 of the member 18 is similarly inclined so as to be substantially parallel with the surface 14 or only slightly more inclined so that the passage between these surfaces is only slightly tapered toward the periphery of element 2. The beater members are in the form of smooth cylindrical rods as shown. The motor 6 is designed to drive the element 2 at a speed of 3600 R. P. M. and the adjusting nut 30 is positioned to maintain an initial and minimum clearance of about .010 inch more or less between the surfaces 14 and 22 of the mixing elements. The device is lowered into a vessel containing the emulsion producing materials and dye and allowed to continue in operation until the desired emulsification and dispersion of the materials and dye has been produced. During initial stages of operation the materials undergoing treatment are relatively fluid and the clearance between the mixing elements is but little if any more than that established by the adjusting nut 30. Under these conditions the materials passing between the surfaces 14 and 22 and actuated by the element 2 serve to cause the low speed mixing element to rotate at approximately 150 R. P. M.

At the same time the dye is dispersed and disintegrated by the surfaces 14 and 22 so as to reduce any lumps or agglomerations of the dye that may be present.

As the operation continues and emulsification is effected the consistency of the material is altered and it becomes "thicker" causing the low speed mixing element 10 to rise reducing the force with which the material tends to drag the element 10 about and increasing the force required to move the agitating members or beater rods 24 through the material. The low speed mixing element thus automatically decreases in speed until it is rotating only relatively slowly.

In other uses of the device, as when dissolving or dispersing solids such as adhesives in liquids, the initial speed of rotation of the low speed mixing element may be relatively slow due to the fluid nature of the mixture but may increase considerably as the consistency of the material changes and its adhesion characteristics increase. An increase in speed of rotation of the low speed mixing element may also occur as the separation of the cooperating surfaces of the mixing elements decreases on dispersion of solids in a liquid medium. Thus in each application of the device the operation adapts itself automatically to the particular conditions to which it is subjected by reason of the floating character and impositive drive of the low speed mixing element. Furthermore, in each application of the device the material undergoing treatment cooperates with the adjacent surfaces of the mixing elements to function as a lower bearing for these elements, keeping them properly centered, so that only a single upper bearing is required to maintain the mixing elements in the proper relation during operation. From the foregoing description it will be apparent that devices embodying my invention are adapted for use in the treatment of a wide variety of materials and in performing various operations. It will also be evident that numerous changes may be made in the form and arrangement of the elements of the device to render it particularly applicable to any special operation. Such alterations are contemplated and comprised within the scope of my invention and therefore it should be understood that the particular form of my invention shown in the drawing and herein described is intended to be illustrative of my invention and is not intended to limit the scope thereof.

I claim:

1. A mixing device comprising driving means, a shaft driven by said means, a mixing element fixed to said shaft and rotatable therewith, a bearing on said shaft and a second mixing element engaging said bearing and freely rotatable about said shaft, said second mixing element having a portion thereof located adjacent said first element in position to be driven impositively thereby through the action of material undergoing treatment and passing between said elements.

2. A mixing device comprising a container for the material to be mixed, two independently rotatable elements located in said container, driving means positively connected to one of said elements, means carried by the second element located adjacent the first for impositively driving the second element through material undergoing treatment and passing between said elements and means carried by said second element and projecting from the second element into contact with other material in said container to insure

relative rotation of said elements during a mixing operation.

3. A mixing device comprising a shaft, an element driven by said shaft, a bearing on said shaft, 5 a second element engaging said bearing and rotatable about said shaft, said second element being longitudinally movable with respect to said shaft and cooperating surfaces on said elements for driving the second element through the action of material undergoing treatment and passing between said surfaces.

4. A mixing device comprising a shaft, a positively driven mixing element connected to said shaft, a floating mixing element rotatable about said shaft and axially movable with respect thereto, spaced parallel surfaces on said elements positioned to cooperate with material passing between the same during operation to center said floating mixing elements with respect to said positively driven mixing element and a slideable and rotatable bearing between said floating mixing element and said shaft and spaced axially from said positively driven mixing element.

5. A mixing device comprising a shaft, a positively driven mixing element connected to said shaft near the lower end thereof, a floating mixing element rotatable about said shaft above the positively driven element and movable axially of said shaft and means for supporting and centering said floating element with respect to the positively driven element including spaced parallel surfaces on said elements, means for passing material undergoing treatment between said surfaces during operation and a slideable and rotatable bearing between said shaft and the floating mixing element and located above and spaced from the positively driven mixing element.

6. A mixing device comprising a shaft, a positively driven mixing element secured to said shaft, a floating mixing element rotatable about said shaft above the positively driven element and axially movable relative to said shaft, said floating mixing element embodying a member having a central opening through which said shaft extends and through which material passes to the positively driven mixing element and also having an outwardly and downwardly inclined surface located adjacent the positively driven mixing element and cooperating therewith to cause material undergoing treatment and actuated by the positively driven mixing element to raise the floating mixing element so that it is supported and rotated by said material.

7. A mixing device comprising a shaft, a positively driven mixing element secured to said shaft, a floating mixing element rotatable about said shaft above the positively driven element and axially movable relative to said shaft, said floating mixing element embodying a member having a central opening through which said shaft extends and through which material passes to the positively driven mixing element and also having an outwardly and downwardly inclined surface located adjacent the positively driven mixing element and cooperating therewith to cause material undergoing treatment and actuated by the positively driven mixing element to raise the floating mixing element so that it is supported and rotated by said material and a slide and rotatable bearing between the floating mixing element and shaft located above and spaced from the positively driven mixing element.

8. A mixing device comprising a shaft, a positively driven mixing element secured to said shaft, a floating mixing element rotatable about

said shaft above the positively driven element and axially movable relative to said shaft, said floating mixing element embodying a member having a central opening through which said shaft extends and through which material passes to the 5 positively driven mixing element and also having an outwardly and downwardly inclined surface located adjacent the positively driven mixing element and cooperating therewith to cause material undergoing treatment and actuated by the positively driven mixing element to raise the floating mixing element so that it is supported and rotated by said material, agitators connected to said member and projecting above the same, means connecting said agitators above said member and 10 15

extending transversely of said shaft and a slideable and rotatable bearing between said means and shaft.

9. A mixing device having a high speed mixing element and a floating mixing element provided with cooperating outwardly and downwardly inclined surfaces positioned to contact the material undergoing treatment to cause material actuated by the high speed element to support and rotate the floating element and means carried by the floating element for retarding rotation of the floating element, said means serving further to mix said material.

SAMUEL K. NESTER.
